UNITED STATES PATENT OFFICE

99,248

DESIGN FOR A SHINGLE STRIP

Joseph J. Piazza, Carlstadt, N. J., assignor to The Patent and Licensing Corporation, New York, N. Y., a corporation of Massachusetts

Application August 23, 1935, Serial No. 58,252

Term of patent 14 years

To all whom it may concern:

Be it known that I, Joseph J. Piazza, a citizen of the United States, residing at Carlstadt, in the county of Bergen and State of New Jersey, have invented a new, original, and ornamental Design for a Shingle Strip, of which the following is a specification, reference being had to the accompanying drawing, forming part thereof.

The figure is a face view of a shingle strip showing my new design.

It is understood that the design claimed may be embodied in a strip of definite or indefinite length which may be used as a roof covering or as a siding or as other building covering without departing from the spirit of the invention.

What I claim is:

The ornamental design for a shingle strip substantially as shown and described.

JOSEPH J. PIAZZA.
